Application March 6, 1931, Serial No. 520,661

21 Claims. (Cl. 123—179)

This invention relates to starting devices for internal combustion engines, and more particularly to a starter of the inertia type.

An object of the invention is to provide a 5 starter of the inertia type embodying a novel method and means for drivably connecting the starting apparatus to a member of the engine to be started.

A further object of the invention is to provide 10 an inertia starter embodying novel driving means for operatively connecting the flywheel with the engine member to be rotated, whereby the energy stored in the flywheel may be imparted to said engine member over a relatively long period.

Another object of the invention is to provide a 15 novel starter of the inertia type which is completely self-contained, and the inertia element of which is preferably mounted above and carried by a member of the engine to be started.

Another object of the invention is to provide a 20 novel inertia starter which is particularly adapted for use in starting outboard motors of the type now extensively employed on small boats.

A further object is to provide a starter of novel 25 construction in which driving engagement is effected by a radial movement of normally withdrawn members into frictional driving relation with a member of the engine to be started.

Another object is to provide an inertia starter 30 employing radially movable driving members so controlled and disposed with respect to the engine member which they drive that their engaging movement occurs automatically following initial rotation of the engine member by another agency.

Another object of the invention is to provide in 35 a manually operated engine starting mechanism employing an inertia element in which energy is stored for subsequent transmission to a member of the engine to be started, novel means for preventing the establishment of driving engagement between the inertia element and engine member until after a predetermined rotation of the engine member, produced by means in- 40

dependent of said inertia element. 45
In cranking an engine by application of energy previously stored in a flywheel or other inertia element, a considerable portion of the stored energy is consumed in the initial effort of turning the engine crankshaft through its first revolution, the turning effort required thereafter being but a small proportion of the initial torque. By providing preliminary cranking means independent of the inertia element of the starter, 50 in conjunction with means for automatically con-

necting the inertia member with the engine member thereafter, it is evident that the engine can be accelerated to self-energizing speed with less power, and the period of application of such power can be prolonged. 5

It is an object of the present invention to provide such a method of starting an engine, and such a combination of cranking and connecting means.

Another object is to provide a novel combination of manually and automatically operable engine starting means, the former being applicable directly to the engine member to produce rotation thereof, and the latter being operable in response to the resultant rotation of said 15 engine member.

A further object is to provide in a combined 20 hand and inertia starter of the foregoing character, novel means for drivably connecting the inertia member with the engine member, said connecting means being operable automatically in response to rotation of said engine member, such automatic action being dependent upon the attainment of either a predetermined speed or a 25 predetermined degree of rotation.

Other objects of the invention reside in the 30 construction and inter-relation of parts and will become apparent from inspection of the following specification when read with reference to the accompanying drawings wherein one embodiment 35 of the invention is illustrated.

In the drawings:

Fig. 1 is a central vertical section of a device embodying the invention;

Fig. 2 is a transverse sectional view along the 35 line 2—2 of Fig. 1;

Fig. 3 is a central vertical section of another embodiment of the invention;

Fig. 4 is a view of a detail of the engaging mechanism of the embodiment of Fig. 3; and 40

Fig. 5 is a transverse sectional view along the line 5—5 of Fig. 3, the view being limited, however, to the part inside the drum portion of the driven mechanism.

Referring to the drawings, and more particularly to Fig. 1, it will be seen that the engine to be started is provided with a rotatable member 5 which, if desired, may be integral with or secured to the crankshaft of the engine, or a member drivably associated therewith. 45

This invention is shown embodied in novel starting or cranking means associated with the rotatable member 5 for developing and transmitting a starting torque to said member whereby the engine may be cranked. As shown, such 55

means includes a housing having a section 6 extending upwardly from around the engine member 5, said housing having an upper section 8 with an outwardly turned marginal flange 9 registering with section 6 and adapted to be supported on an inwardly turned flange 10 on the section 6, suitable means such as screws 12 being provided to rigidly secure the flange 9 of section 8 to the flange 10 of section 6. The upper portion of section 8 is preferably provided with a centrally disposed hub 13 having a central opening through which extends the cylindrical hub 14 of a yoke or spider member 15 provided for a purpose presently to be described.

Suitable means are employed for storing up energy to be subsequently used at the will of the operator for rotating the engine member 5 and thereby starting the engine. As shown, such means is preferably constituted by an inertia member adapted to be rotated at high speed through suitable gearing drivably connected to a cranking member, the gearing being preferably divided into two or more stages. For this purpose, the spider 15 above referred to is provided with a plurality of supporting posts 16 extending downwardly to retain in place an annular member or ring 17 on which is rotatably supported, with the aid of ball bearings 19, a corresponding number of driving gears 20 adapted 25 to mesh with a sun gear or pinion 21 and also with the teeth of an internal or annular gear 22 which is secured to the housing section 8 by suitable means as indicated at 23. As shown, the gears 20, 21 and 22 constitute a planetary system of gears operating in response to rotation of member 14 to impart rotation at a multiplied speed to the inertia means to be described, the gear 21 being preferably integral with a centrally disposed shaft 25.

Appropriate means are provided for drivably connecting the shaft 25 with the second stage of the gearing which leads to the inertia member. As shown, such means preferably involves the provision at the lower end of shaft 25 of a recessed apertured plate or spider 26 rotatable in response to rotation of the sun gear 21 by the means above described. The supporting means for spider 26 may be of any suitable form, but as shown, consists in the provision of a threaded reduced portion at the lower end of shaft 25 to which is secured a nut 27 adapted to hold in place, with the aid of locking washer 28, the aforesaid spider 26. Near the outer periphery of spider 26 are located a plurality of supporting posts or bolts 30 having threaded lower ends 31 for a purpose to be described, said bolts being adapted to rotatably receive a corresponding number of gears 32, the bolts being preferably enlarged, as indicated at 33, to form heads 50 resting on bearings 34, the latter being provided to facilitate rotation of said gears. The rotation of these gears about the posts 30 is preferably brought about by providing an internal gear 36 which, is shown as fixed relatively to the gears 32 by virtue of the provision of the above described bolts 12 interposed between the said gear and the casing.

The preferred means for imparting rotation to the inertia member at a greatly multiplied speed, in response to the rotation of the member 14, further includes a second sun gear or pinion 37 having teeth meshing with the teeth of the gears 32 and hence adapted to be rotated thereby, the gear 37 being rigidly secured to a member 38 by suitable means, which as illustrated,

takes the form of splines 39, a retaining nut 40 being threaded to the lower end of member 38. Member 38 is in turn rotatable relatively to the driving shaft 25, the relative rotation between the two being facilitated by the provision of suitable bearing means as indicated at 42. The member 38 is also provided at its upper end with an outwardly turned flange 43 adapted to be secured to an inertia member 44 by suitable means which in the form shown comprises a plurality 10 of studs or rivets 45 rigidly connecting the flange 43 with an inwardly extending annular flange 46 provided on the inertia member, or flywheel, 44.

The bolts 12 also serve to hold in place a transversely disposed plate or partition 51 which is 15 adapted to support a ball bearing 52 representing any suitable means upon which the flywheel 44 and flanged member 38 may be rotatably mounted, the ball bearing member 52 being preferably adapted to rest at its outer edge on the supporting plate 53 rigidly fastened to the partition 51 by suitable means as indicated at 54.

Any suitable manually operated means may be provided for rotating the hub 14 to store energy in the inertia member 44 through the speed 25 multiplying mechanism above described. As illustrated in Fig. 1 such means preferably comprises the provision of a threaded upper portion on member 14 for engagement with an internally threaded member 55 having a transversely extending section which at its outer edge turns in a downward direction to form a sleeve to which any suitable crank or other hand turning device (not shown) may be attached.

Appropriate means are provided for operatively connecting the flywheel 44, after the desired amount of energy has been stored therein to the engine member 5. Such novel means preferably comprises the provision of a cylindrical member or drum, such as that indicated at 65, 40 rigidly secured to the shaft 5, in combination with a plurality of elements such as those indicated at 66 and 67 (Figs. 1 and 2) having convex frictional surfaces adapted to be moved radially into engagement with the drum 65 by operation of the meshing means to be described.

These radially movable elements 66 and 67 are adapted to rotate with the recessed plate or spider 26 to which said elements are pivotally secured by suitable means, as, for example, the transversely extending arms 69 (Fig. 2) provided with apertures for reception of bolts 68, the bolts being held in place by suitable means, as, for example, the nuts 72, (Figs. 1 and 4) engaging the lower threaded ends thereof. On the convex arcuate 55 rims of elements 66 and 67 are provided correspondingly shaped bands 74 of suitable friction material, the curvature of these bands being preferably such as to render the elements 66 and 67 self-energizing, that is, cause them to wrap themselves snugly against the inner surface of drum 65 upon radial movement from their normal positions as shown in Fig. 1.

Suitable means are provided for maintaining the members 66 and 67 in non-engaging position 65 with respect to the drum 65 notwithstanding the tendency of such elements to move outward radially in response to the centrifugal force resulting from rotation of these elements during the cranking operation. As shown, such means comprises, first, a plurality of resilient means so positioned as to oppose the centrifugal action, and secondly, the provision of suitable counterbalancing means also tending to oppose the centrifugal action. The resilient means preferably comprises 75

5 a pair of springs, 77 and 78 (Figs. 1 and 2) the former being fastened at one end to the element 67 and at its other end to the lower end of one post 30, while the latter is fastened to the element 66 at one end and at the other end to the other post 30, the points of attachment being so located 10 with respect to the pivots 68 on which the friction elements are suspended, and with respect to the axis of rotation of these elements, that they exert a resilient force in opposition to the centrifugal force resulting from rotation of the parts.

10 The counterbalancing means which preferably act in conjunction with the above described resilient means to oppose the centrifugal force created by the rotation of members 66 and 67, and maintain such elements in non-driving position during cranking operation, are constituted by a 15 pair of weighted arcuate members 79 and 80 rigidly secured, as by rivets, 81, to the outer ends of the cross-arms 69. These counterweights 79 and 20 80 are respectively positioned diametrically opposite to the arcuate driving elements 66 and 67, so as to have maximum counterbalancing effect, the 25 elements all being preferably unsymmetrically located with respect to the cross-arms 69 (as shown in Fig. 2). This unsymmetrical mounting of the 30 friction elements and counterweights also has the advantage of permitting the arrangement of the cross-arms 69 in parallelism as indicated in Fig. 2. It will also be noted that the counterbalancing 35 weights 79 are attached to the cross-arms 69 in such a manner as to permit superimposing the friction elements 66 and 67 thereupon, as indicated.

40 There will next be described that feature of the invention which consists in providing novel means to move the elements 66 and 67 outwardly in a radial direction into frictional driving contact with the surface of drum 65, such novel means also operating to impart rotation to the engine member 5. For this purpose the cross-arms 69 are preferably provided with sloping shoulders, as indicated at 82, spaced apart sufficiently to permit their being engaged by the centrally and vertically disposed rod 83, having a correspondingly tapering shoulder 84, the degree of taper being such that upon downward movement of rod 83 a wedging action is produced which moves the cross-arms 69 away from each 45 other, thereby moving the friction elements 66 and 67 into engagement with the drum 65.

50 Associated with the drum 65 is a plate or cam member 85 secured by suitable means 86 to the lower end of rod 83, the plate having an annular ridge 87 adapted to be engaged by fingers 88 on arms 89, the latter constituting extensions of the weighted members 90 slidably mounted on guide members 91 secured by suitable means, as indicated at 92 to opposite points on the inner surface 55 of drum 65. At corresponding points on the outer surface of the drum the fastening means 92 preferably engage and hold in position a circumferential flange or track 94 on which a hand rope 95 or other turning means may be placed.

60 The weights 90 are preferably provided with laterally disposed openings 96 serving for reception of the ends of laterally projecting pins 97 attached at opposite points on casing 65 by suitable means as indicated at 98. A recess 99 is also 65 preferably provided on weights 90 to serve as a seat for compression springs 100, the function of the latter being to normally hold the weights 90 in the positions indicated, to resist outward radial movement of said weights in response to the cen- 70

trifugal force created by rotation of drum 65, and to return the arms 89 after the engine stops.

Having thus identified the parts entering into the construction illustrated in Figs. 1 and 2, the operation of this embodiment of the invention 5 will now be described.

When it is desired to start the engine, the sleeve 55 is rotated by means of a suitable handle 61 (which may or may not remain in place at all times) such rotation operating to store energy 10 in flywheel 44 through the speed multiplying means above described, the path of transmission being from the member 55 to the hub 14, spider 15, and planetary gears 20 to the sun gear 21, thence through shaft 25 to the spider 26, and 15 thence to the planetary gears 32, sun gear 37 and hub 38 to the flywheel 44.

When the flywheel has by the foregoing means been brought up to a speed sufficient to store the desired amount of energy for use in cranking the 20 engine, the operator effects an initial turning of the engine member 5, by exerting a pull on the rope attached to the track 94, or in any other convenient manner.

Rotation thus imparted to the members 65 and 25 5 (the latter being riveted to the former as shown at 102 and 103) creates a centrifugal force acting upon the weights 90 to cause them to move outward radially against the force of springs 100 thereby producing engagement between fingers 30 88 and the ridge 87, which engagement causes a corresponding downward movement of the rod 83. The downward movement of rod 83 thus effected causes a corresponding radial movement of members 66 and 67 into engagement with the 35 surface of drum 65. With such engagement established, the energy stored in flywheel 44 will continue rotation of the engine without further action on the part of the operator, the rotation of the engine being continued by this means for 40 a much longer period than would be possible were it necessary to utilize the energy of the flywheel for overcoming the static inertia of the engine.

After the engine stops, springs 100 act to return arms 89; springs 104, 71, and 78 having 45 meanwhile returned rod 83 and shoes 66 and 67 to their respective normal positions as shown in Fig. 1.

There is thus provided a novel engine starter of the inertia type which is simple and rugged 50 in structure, inexpensive to manufacture and efficient in operation. It is especially adapted for use with small engines because of its compactness and light weight, but since it is a self-contained unit it may be easily attached to any engine 55 and requires no external supporting means, the whole unit in the embodiment shown being mounted within an extension of the engine housing and part of the mechanism being carried by a rotating member of the engine. 60

If desired, the invention may be embodied in a starter of the reaction type, wherein the entire mechanism is carried by, and rotates with, the engine member to be cranked. Such an embodiment is illustrated in Figs. 3, 4, and 5 and may 65 be constituted by an engine member 105 secured to the engine shaft 106 by suitable means as indicated at 107 and 108, the member 108 also preferably serving for attachment of the starter housing. The starter housing preferably is composed of three sections 111, 112, and 113 secured together by suitable means such as screws 114 passing from the horizontally disposed surface of the upper section 113 through the cylindrical wall and the central section 112 and threadedly 70 75

engaging the upper circumferential flange on the lower section 111. The upper section 113 is provided with a circumferentially extending groove 116 for attachment of a rope 115 or other actuating means, and is further provided with a hub portion 117 rotatable relatively to the hub 118 of spider 119 the latter having a function now to be described.

Spider 119 constitutes the driving or cranking member for the inertia element of this embodiment of the invention. To this end the spider is provided with a plurality of supporting screws 123 located at equal angular distances about the former and near the outer edge thereof, said screws being received in spacer sleeves 124 and adapted to rotatably support, with the assistance of ball bearings 125, a corresponding number of driving gears 126 adapted to mesh with a sun gear or pinion 121 integral with a centrally disposed shaft 122, the gears 126 also meshing with the teeth of an internal gear 127 mounted in the recesses formed in the abutting edges of sections 112 and 113, the gears 121, 126, and 127, thus constituting a planetary system of gears operable in response to manual rotation of the member 118 produced by means of a threaded connection between said member and the sleeve 132, the latter having means 133 thereon for attachment of a suitable handcrank 134.

The inertia member of the starting mechanism of this embodiment of the invention is adapted to be operatively connected to the sun gear 121 and driven thereby through suitable friction clutch means. As shown, such inertia member comprises an annular rim 135 of suitable weight and mass having near its lower edge a flanged portion 136 presenting upper and lower flat annular surfaces for the reception of friction discs 137 and 138 associated with clutch members 139 and 140 respectively, the member 140 having a cylindrical hub or boss 141 extending upwardly at right angles thereto but integral therewith and provided near its upper edge with a portion 142 adapted to engage a correspondingly threaded hub formed on the ring 143.

Means for regulating the frictional pressure brought to bear on the flywheel 135 through the medium of members 139 and 140 preferably includes a nest of coiled springs 146 properly spaced and held in position by the provision of studs 147 riveted or otherwise suitably secured in suitable openings in the ring 144, the upper ends of the springs 146 bearing against the under surface of the ring 144 which is vertically movable to vary the tension of the springs by virtue of the provision of the threaded connection with the hub of the member 140.

The means for causing the clutch members 139 and 140 to rotate in response to rotation of shaft 122, and thereby store energy in the flywheel 135 to be subsequently used in starting the engine, preferably comprises the provision of a flanged formation at the lower end of shaft 122 as indicated at 150, the said flange being provided with a plurality of openings for the reception of screws 151, to the lower threaded ends of which is secured the clutch member 140, the said member having an inwardly extending flanged section provided with threaded openings for the reception of said screws 151. The member 140 is further provided with a depending hub or boss 155 which, together with the cooperating threaded cylindrical members 156 and 157 (supported on the upwardly projecting flange 158 formed on transversely disposed plate 159) form a pocket for the

reception of ball bearing 162 on which the members 150 and 140, and hence the flywheel 135, are rotatably supported.

The mechanism described above constitutes means for storing up energy to be subsequently used at the will of the operator, for cranking and starting the engine. There will now be described the novel means which are provided for operatively connecting the flywheel 135, after the desired amount of energy has been stored there-in, to a member of the engine to be started. Generically speaking, said means comprises, first, a mechanism constantly tending to effect operative driving engagement with the casing 111 in response to the transmission of torque through the 10 rotating flywheel; and secondly, means normally preventing said mechanism from following such tendency; and thirdly, a manually operable device for rendering said second named means ineffective and thereby permitting said engaging 15 mechanism to effect driving connection with the member 111.

The engaging mechanism normally tending to effect driving connection, comprises a plurality of (as shown two) speed responsive elements 160 25 and 161 pivotally mounted on studs 103 and 103', respectively, these studs being located in openings provided on flange 165 formed at the lower end of shaft 166, the latter being splined or otherwise secured to member 155 for rotation 30 therewith, and locked against longitudinal movement relative thereto by suitable keying and supporting means as shown at 152.

The sector-shaped elements 160 and 161 are provided at their outer arcuate rims with correspondingly shaped friction plates 164, formed along the outer edges thereof and having a curvature corresponding to the curvature of the drum 111, the elements 160 and 161 being normally restrained (by means hereinafter described) from following the tendency to move radially outward into engagement with the inner surface of drum 111 in response to centrifugal force set up by the rotation of the member 165 and corresponding rotation of the sectors 160 45 and 161.

The novel means for releasing the restraint on elements 160 and 161 and at the same time imparting initial rotary movement to the engine will now be described. It will be seen that the 50 members 160 and 161 are provided with downwardly extending lugs or fingers 169 adjacent which there is provided a cup-shaped member 171 the vertical cylindrical wall of which is adapted to surround and enclose the fingers 169 55 and thereby prevent radial movement of the members 160 and 161 so long as the cup member 171 remains in the position shown in Fig. 3. The latter is normally held in this position by the provision of a nut 172 threaded to the lower end of 60 rod 173. A cap 175 is secured to the upper end of rod 173, the rod being held in the position indicated in the drawings by suitable resilient means 176 which, resting on stationary collar 177, normally presses upward against the cap 175. 65

Novel means are provided for engagement with the cap 175 at the proper time to cause release of members 160 and 161 in response to independent rotation of the housing. As shown, such means includes an arm 180 connected by suitable 70 means 181 to a second arm 182, having at its outer end a finger 183 (Figs. 3 and 4) adapted to follow the coarse thread 184 formed on the member 185, the latter extending circumferentially about casing 111 and being secured thereto by suitable 75

means, preferably screws 114. The arms 180 and 182 are preferably movable to and from operative position by suitable means which, in the embodiment illustrated, comprises preferably a swivel pin 186 provided in a bearing 187 secured to the upper end 188 of a bracket 189, the latter being secured by suitable means as indicated at 190 to the stationary engine support 191.

In operation, the handcrank 134 is connected with sleeve 132, and hub 118 is rotated until the flywheel is brought up to a speed sufficient to store the desired amount of energy for use in starting the engine, the storing of energy in the flywheel being effected through the transmission means including spider 119, planetary gears 126 and 127, pinion 121, and friction clutch members 160 and 161. It will be noted that the rotating starter elements, including the members 140, 135, 166, 160, and 161, are out of engagement with the member 111 during the time that energy is being stored in the inertia member.

Following such acceleration of the flywheel, arms 180 and 182 are swung into operative position. The starter housing and engine shaft are now rotated by a rope or other suitable means engageable with groove 116 to impart initial rotary movement to overcome the static inertia of the parts. When the rotation has proceeded sufficiently so that the revolution of the coarsely threaded surface 185 produces a downward travel of the pin 183 sufficiently to produce the required downward movement of the rod 173 by the pressure of arm 180 upon the cap 175, the clamp 171 is released from its restraining relation to the fingers 169, whereupon sector elements 160 and 161 engage the casing 111 by action of centrifugal force, and such engagement makes it possible to continue the cranking operation without further act of the operator until the speed of the flywheel is spent. By this means the energy of the flywheel, none of which has been expended in overcoming the static inertia of the engine, will be sufficient to bring the engine up to a speed permitting starting under its own power.

It will be noted that during cranking of the engine the starter elements remain drivably connected to the engine crankshaft. This is due to the nature of the engagement between the members 160 and 161, on the one hand, and drum 111, on the other hand, the shape and method of mounting of which causes these members to maintain driving contact so long as they are rotating at a speed sufficiently high to overbalance the opposing effect of springs 102 and 102'. Moreover, these sector elements are such as to render them "self-energizing", that is, cause them to grip the drum with a force which increases from the initial engaging force to a much greater maximum, which force is a cumulative resultant of the centrifugal force due to rotation, plus the force tending to turn the sector elements about their pivots eccentrically, both of which forces are exerted directly against the surface of the drum 111.

From the foregoing it will be seen that the mechanism performs the dual function of starter and engine fly-wheel, while a restarting can be effected by utilizing the energy remaining in the flywheel, which will continue to rotate for a considerable period after the engine power has been cut off. When this energy is dissipated, the springs 102 and 102' will, of course, act to withdraw the elements 160 and 161 and return them to the position shown in Fig. 3, thereby permitting the spring 176 to return cup member 171

to locking relation with respect to the fingers 169 and 170, such return having been prevented theretofore by the continued contact of the elements 160 and 161 with the upper surface of the cup member 171.

It will be obvious that the invention is not limited in form to either of the embodiments above described, nor is it limited to the specific use described, but is capable of a variety of mechanical embodiments and uses.

What is claimed is:

1. The method of starting an internal combustion engine which comprises first energizing an inertia element to a speed much higher than the normal speed of the engine to be started, then imparting an initial rotation to the engine by means independent of said inertia element, and finally drivably connecting said inertia element to the engine when the latter has been rotated by operation of said independent means. 20

2. In an engine starting mechanism of the type embodying a flywheel in which energy is stored for subsequent transmission to a member of the engine to be started, the combination with said flywheel and engine member of means independent of said flywheel for imparting an initial rotary movement to said engine member, and means operable in response to the operation of said independent means to drivably connect said flywheel and engine member. 30

3. In combination with a rotatable member of an engine to be started, a cylindrical member drivably connected to said engine member, a flywheel in which energy is stored for starting the engine, said flywheel being adapted for rotation relative to said cylindrical member during the energy storing operation, means for rotating said cylindrical member and engine member relatively to said flywheel, and means operable in response to actuation of said last named means 40 to drivably connect said flywheel and cylindrical member to cause a transmission of starting torque through said cylindrical member to said engine member. 35

4. An engine starting mechanism comprising 45 in combination with a rotatable member of an engine to be started, means for preliminarily rotating said engine member, a driving member, torque transmitting means adapted to drivably connect said members including a friction member 50 connected to said driving member and adapted for movement into engagement with said engine member, and means operable in response to said preliminary rotation of said engine member 55 to cause movement of said friction member into engagement with said engine member.

5. An engine starting mechanism comprising in combination with an inertia member in which energy is stored for subsequent transmission to a member of the engine to be started, means for 60 preliminarily rotating said engine member, torque transmitting means adapted to drivably connect said members and including a friction element connected to the inertia member and movable into engagement with the engine member, 65 and means operable in response to said preliminary rotation of the engine member to cause said friction member to drivably connect said inertia and engine members.

6. In combination, a driving member, a rotatable driven member, means for preliminarily rotating said driven member, torque transmitting means adapted to drivably connect said members and including a friction member connected to the driving member, and centrifugally respon- 75

sive means carried by said driven member for automatically moving said friction member radially into driving engagement with the driven member in response to said preliminary rotation of the driven member.

7. In combination with friction elements of the self-energizing type, a driven member adapted to be engaged thereby, means for preliminarily rotating said driven member, means tending to move said friction elements into engagement with said member, means normally preventing such movement, and means for releasing said preventing means comprising a member engageable with said preventing means in response to a predetermined degree of said preliminary rotation of said driven member.

8. In an engine starting mechanism employing friction elements of the self-energizing type adapted to drivably connect the starting mechanism with a member of the engine to be started, means for preliminarily rotating said engine member, means tending to move said friction elements into engagement with said engine member, means normally preventing such movement, means for releasing said preventing means, and means operable in response to a predetermined degree of said preliminary rotation of said engine member to actuate said releasing means.

9. In an engine starting mechanism employing friction elements of the self-energizing type adapted to drivably connect the starting mechanism with a member of the engine to be started, means for preliminarily rotating said engine member, means tending to move said friction elements into engagement with said engine member, means normally preventing such movement, means for releasing said preventing means, and means operable in response to a predetermined degree of said preliminary rotation of said engine member to actuate said releasing means, said last named means comprising an arm engageable with said releasing means, a threaded member rotatable with said engine member, and a follower operatively connected with said arm and movable along the thread of said threaded member in response to rotation thereof.

10. In combination with a cylindrical member, means for preliminarily rotating said cylindrical member, a shaft mounted within said cylindrical member and rotatable relatively thereto, means for drivably connecting said shaft and cylindrical member comprising a plurality of radially movable elements supported by said shaft, said elements having arcuate surfaces whose degree of curvature corresponds to the curvature of said cylindrical member, means normally preventing radial movement of said elements towards said cylindrical member, and means for causing said radial movement notwithstanding said preventing means, said last named means including a member engageable with said radially movable elements and adapted to be actuated in response to said preliminary rotation of said cylindrical member.

11. In combination with friction driving elements, a rotatable member adapted to be engaged and rotated by said friction elements, means for preliminarily rotating said rotatable member, means for controlling the movement of said friction elements into engagement with said driven member, said controlling means comprising a member movable at right angles to the plane of movement of said friction elements and engageable therewith, and means for actuating said controlling means after said preliminary rotation,

said actuating means comprising a member rotatable with said driven member, a follower movable along the axis of rotation of said driven member, and means connecting said controlling member with said follower for movement therewith.

12. In combination with friction driving elements, a rotatable member adapted to be engaged and rotated by said friction elements, means for preliminarily rotating said rotatable member, means for controlling the movement of said friction elements into engagement with said driven member, said controlling means comprising a member movable at right angles to the plane of movement of said friction elements and engageable therewith, and means for actuating said controlling means after said preliminary rotation, said actuating means comprising a member rotatable with said driven member, a follower movable along a path parallel to the axis of rotation of said driven member, and means responsive to movement of said follower to cause corresponding movement of said controlling member.

13. Engine starting mechanism comprising a driving member and a drive transmitting member movable into position to operatively connect said driving member to a member of the engine to be started, means normally preventing such movement of said drive transmitting member, and means for releasing said preventing means comprising a member mounted adjacent said starting mechanism, and manually movable into position, to cause movement of said preventing means out of restraining relation to said drive transmitting member.

14. In an engine starting mechanism, in combination with a driving member movable to engage a member of the engine to be started, means for preliminarily rotating said engine member, a longitudinally movable member controlling the movement of said driving member, and means engageable with both said engine member and said longitudinally movable member to actuate the latter in response to said preliminary rotation of said engine member.

15. In a device of the class described, in combination with a member to be rotated, means for preliminarily rotating said member, a driving member normally out of engagement therewith, a longitudinally movable member for thereafter controlling the establishment of driving relation between said first named members, a follower movable longitudinally in response to rotation of said member to be rotated, and means for rigidly connecting said follower to said controlling member to produce a corresponding longitudinal movement of said controlling member.

16. In a driving mechanism, in combination with driving and driven members and controlling means therefor, said controlling means comprising an elongated member disposed in coaxial relation thereto, means for preliminarily rotating said driven member, a grooved member connected to said driven member for rotation therewith during operation of said preliminarily rotating means, a follower movable in the groove of said grooved member to describe a rectilinear path parallel to the axis of rotation of said grooved member, and means for imparting an axial movement to said elongated member in response to rectilinear movement of said follower.

17. In a driving mechanism, in combination with driving and driven members and an elongated member disposed in coaxial relation thereto,

means for preliminarily rotating said driven member, a radially movable meshing member connected to said driven member for rotation therewith during operation of said preliminarily rotating means, and means for imparting an axial movement to said elongated member in response to radial movement of said meshing member, said means comprising a cam surfaced member secured to said elongated member, and projecting 10 into the path of said meshing member.

18. In combination with driving and driven members, means for drivably connecting said members comprising a rod disposed in coaxial relation thereto, means for preliminarily rotating 15 said driven member and means for transmitting an axial movement to said rod in response to said preliminary rotary movement of said driven member, said transmitting means comprising a pair of arms pivotally supported adjacent said 20 members and adapted to be swung into operative relation to said rod and driven member.

19. In combination with driving and driven members, means for drivably connecting said members comprising a rod disposed in coaxial 25 relation thereto, means for preliminarily rotating said driven member and means for transmitting an axial movement to said rod in response to said preliminary rotary movement of said driven member, said transmitting means comprising a 30 pair of arms pivotally supported adjacent said members and adapted to be swung into position to

constitute a connecting linkage between said driven member and said rod, whereby rotary movement of said driven member produces corresponding axial movement of said rod.

20. In combination with driving and driven members, means for drivably connecting said members comprising a rod disposed in coaxial relation thereto, means for preliminarily rotating said driven member and means for transmitting an axial movement to said rod in response 10 to said preliminary rotary movement of said driven member, said transmitting means comprising a pair of arms slidably mounted with respect to said driven member and adapted to be moved radially by centrifugal action to constitute 15 an actuating linkage between said driven member and said rod.

21. In combination with driving and driven members, means for drivably connecting said members comprising a rod disposed in coaxial 20 relation thereto, means for preliminarily rotating said driven member, and means for transmitting an axial movement to said rod in response to said preliminary rotary movement of said driven member, said transmitting means comprising a pair of arms pivotally mounted proximate to said driven member and constituting an actuating linkage between said driven member and said rod.
